CHAIN

John Alan Goode, Birmingham, England

Application April 29, 1948, Serial No. 24,078
In Great Britain August 28, 1946

4 Claims. (Cl. 58—80)

1

This invention relates to chains, and although applicable to chains generally, is primarily intended for application to chains used for personal wear, or ornaments, such, for instance, as flexible bracelets.

The object of the present invention is to provide an improved construction.

A chain constructed in accordance with the present invention comprises links which are connected together by providing one of each adjacent pair with an end portion having lateral projections, which end portion is passed through an opening in the adjacent link and prevented from returning by folding the longitudinal edge portions of the said adjacent link inwardly so as to reduce the effective width of the opening. For instance, the chain may comprise two types of link, i. e. inside links which are of approximately H form having lateral projections at both edges and at both ends, and links in the form of open frames through which the end portions of the adjacent link can be passed, after which the longitudinal edge portions of the frame link are doubled inwardly until they lie against one side of the link with their edge portions overlapping the longitudinal sides of the opening, thus reducing its effective width and preventing the withdrawal of the end portions of the companion link.

When constructed for use as a flexible bracelet, all the links may be bent into curved form in the side view so as to conform to the contour of the wrist. This may be done before assembly in the case of the links having the lateral projections, and may be done after assembly in the case of the open-frame link.

The invention is illustrated in the accompanying drawings, wherein:

Figure 1 shows a metal blank from which the one type of link shown in Figure 2 is made, Figure 2 being to a larger scale than Figure 1 and Figure 3;

Figure 3 shows the blank from which the frame link is made;

Figure 4 shows the method of interconnecting the two links; and

Figure 5 shows part of a finished chain.

In the construction shown in the accompanying drawings, each of one set of links is made from a metal blank (Figure 1) of H form having a central part 10 connecting two end limbs 11. The end limbs 11 are folded or rolled (as in Figure 2) into cylindrical form, and the link as a whole is then bent into curved or similar form

with the cylindrical heads 12 at its ends disposed on the concave side.

The companion links 13 are of rectangular form and are provided with rectangular openings 14 of a width equal to the length of the head formed at the end of the H link.

The heads 12 at the ends of two of the H links are passed into and through the openings 14 of a frame link 13, and the longitudinal edge portions 15 of the frame link 13 are each folded about a line 16 parallel to the longitudinal edges and preferably disposed between the longitudinal edges of the opening and the outside edges of the link. The two portions 15 are doubled inwardly until they lie against the surface of the link with the longitudinal edge portions 15 overlapping the sides of the opening, and thus reducing its effective width so that the heads 12 of the H link cannot be withdrawn. The space between the longitudinal edges of the folded-in parts of the frame link 13 is preferably slightly greater than the width of the intermediate parts of the H link.

When the links have been assembled together 25 in the manner described the frame links 13 can be acted upon by suitable tools so as to bend them into curved or similar form conforming to the contour of the wrist, so as to give a chain having curved links as shown in Figure 5.

In the completed chain the cylindrical end portions 12 of the H link are disposed on the inner side of the chain.

The length of the opening in the open frame link 13 should be a little greater than twice the width or diameter of one of the heads 12 on the H link, but should not be so great as to allow the H link to be detached from the open frame link. The diagonal of the said opening after the folding-in of the edges should be rather less than the length of the head of the H link.

40 The head 12 instead of being of circular cross section may be flat, or of any other shape in cross section. Further, instead of forming the head by bending the metal into tubular form, the head may be solid, in which case the links and head 45 may be made as stampings.

What I claim then is:

1. In a chain, adjacent pairs of links, each pair comprising a link with an end portion having lateral projections and a link having an opening 50 therein of which corresponding to the length of said projections and of length not substantially greater than twice the width of said projections, said links being connected together by passing said end portion of the first link through the opening in the second link, longitudinal edge por-

tions of said second link being subsequently folded back on said link so as to extend over opposite edges of said opening, thereby to reduce the effective width of said opening and to prevent withdrawal of said first link.

2. In a chain, adjacent pairs of links, each pair comprising a link of approximately H form having lateral projections at both edges and at both ends and a link in the form of frame having a substantially rectangular opening therein of width corresponding to the length of said projections and of length not substantially greater than twice the width of said projections, said links being connected together by passing an end portion of the H form link through the opening in the frame link, longitudinal edge portions of said frame link being subsequently folded back on said link to extend over opposite edges of the opening by an amount reducing the width of the opening to that of the central portion of the H-form link, thereby to prevent withdrawal of said H link.

3. In a chain, adjacent pairs of links, each pair comprising a link formed from a metal blank of approximately H form having lateral projections at both edges and at both ends, said end projections being rolled to form cylindrical heads, and a link in the form of an open frame, said links being connected together by passing the end portion of the H form link through the opening in

the frame link, longitudinal edge portions of said frame link being subsequently folded inwardly until they lie against one side of the frame link with their edge portions over-lapping the longitudinal sides of the opening to reduce the effective width of said opening so as to prevent withdrawal of said H link.

4. In a chain, adjacent pairs of links, each pair comprising a link of approximately H form bent into curved formation, having lateral projections at both edges and at both ends and a link in the form of an open frame bent into curved formation, said links being connected together by passing an end portion of the H form link through the opening in the frame link, longitudinal edge portions of said frame link being subsequently folded inwardly to reduce the effective width of said opening so as to prevent withdrawal of said H links; the curvature of said links being such as to conform to the contour of a wrist.
